APPARATUS FOR MILLING FABRICS

Emile B. Bates, Leicester, England

Application March 14, 1949, Serial No. 81,258
In Great Britain March 16, 1948

11 Claims. (Cl. 26—21)

1

This invention concerns a milling apparatus for the milling (or fulling or felting) of fabric (particularly knitted fabric incorporating woollen yarn) and milling apparatus. It is common practice to mill woollen fabric (i. e. to submit it to a mechanical kneading process) in order to increase its thickness and specific weight by producing a decrease in its surface area. The milling operation is, however, to a certain extent haphazard in that it is extremely difficult to judge when the desired result, in the terms of weight per unit area, or weight per unit length of fabric of a predetermined width, has been achieved and an object of the present invention is to provide an apparatus which facilitates the achievement of this desired result.

Experiments have shown that the proportionate reduction in length of the fabric as the milling operation proceeds affords a useful indication of the proportionate increase in weight. The present invention is based on these observations, and provides the steps, in the milling of fabric, of passing the fabric in the form of an endless band repeatedly through the milling machine and obtaining at each of successive passes of the band through the machine a measurement which is representative of the length of the band at that pass. Therefore the progressive reduction in length may be noted and the milling operation may be stopped at a stage whereat experience dictates that the length reduction achieved will give the desired increase in thickness and weight. The measurement, representative of the length of the band, may be obtained by measuring the length but since practical considerations will invariably result in the machine being run at a constant speed it will be appreciated that the time taken for each pass is representative of the length of the fabric band at that pass, and so the length-representing measurement may be a time measurement.

The invention further provides a milling machine of the type comprising a pair of rollers between which the fabric in the form of an endless band is passed repeatedly, a channel or spout or crimp box into which the fabric passes from the rollers and in which it is accumulated and from which it is withdrawn to enter the rollers again, and pressure means for pressing upon the accumulated fabric in the spout; having means for obtaining and exhibiting at each of successive passes of the band a measurement which is representative of the length of the band at that pass. While it is within the scope of the invention to obtain and exhibit the length-representation at each and every pass yet the expression "successive passes" is not to be interpreted as being restricted in this manner for it is within the scope of the invention to obtain and exhibit the length-representation at predetermined passes in the succession, for example at every second or third pass. The means for obtaining and exhibiting the length-representation may com-

2

prise a feeler responsive to the passage through the machine of a local thickness in the fabric (e. g. by the passage of a seam or other device joining the ends of a finite length of fabric into an endless band). If the length-representation is in the nature of a time measurement, it may be obtained by a "stop-watch" mechanism and the feeler may serve to start, stop, and reset this mechanism; if this mechanism follows normal practice a length-representation would thereby be obtained every third pass. In a preferred construction, however, the machine incorporates a length-indicator driven by or in conformity with a measuring roller or the like that engages the fabric, and means operable by the feeler for causing the indicator to be reset for a fresh indication. The feeler may be identified with the roller and this roller may be in addition to the pair of rollers before mentioned or it may be one of these rollers.

The foregoing and other features of the invention are incorporated in the machine which will now be described by way of example, and which is illustrated more or less diagrammatically in the accompanying drawing in which

Figure 1 is a composite figure; the top right hand portion depicts, on a very small scale and somewhat diagrammatically, a milling machine and the remainder depicts, in sectional elevation and on a larger scale, the length-measuring and indicating mechanism;

Figure 2 shows a cross-section through the said mechanism on the line 2—2 of Figure 1;

Figure 3 is a plan of a portion of the mechanism;

Figures 4 and 5 are views illustrating, in front elevation, the operation of the mechanism.

The invention is best carried into effect in a rotary milling machine 1 of the type comprising upper and lower squeezing rollers, 2 and 3 respectively, wherein one and preferably the upper one is biased towards the other. For example the roller may be biased by springs such as the compression springs 4, by gravity or by both. One of these rollers is driven so that the fabric F is passed through the nip between them. Thence the fabric is delivered into a box-like channel or spout 5 (sometimes known as a crimp box) having open ends. The base of this channel at the entry end is located in close proximity to the periphery of the lower roller 3 so that the fabric F is thereby stripped from the latter. In this channel the fabric is caused to accumulate in zig-zag manner, for which purpose and as is well known the channel is provided with a lid 6 which is hinged at its end nearest to the rollers (e. g. about the axis of roller 2) and is weighted so as to press down upon the accumulated fabric. From the other end of the channel the fabric is withdrawn and is conducted again to the rollers.

The milling operation is therefore of a continuous character.

As will readily be understood the fabric is re-

quired to be in the form of an endless band and for this purpose the ends of the fabric band are sewn or otherwise temporarily fastened together. This joint produces a local thickness in the fabric, as indicated diagrammatically at 1, and every time this joint passes between the two rollers 23 the latter are temporarily forced apart. The rotation of these rollers is employed to measure the length of fabric which passes through the nip in the time interval between two successive passages of the joint 1. For this purpose one of the rollers, and preferably the bottom roller 3, is a length measuring device and is connected through suitable reduction gearing (here shown as comprising worm and worm wheel mechanism 8) to a length-indicating device 9 which latter has two indicating fingers 10 and 11 movable over a dial a portion of which is represented in dotted lines at 12. The finger 10 is caused to advance from the zero position at every third pass of the seam 7 by a clutch which is controlled by the lifting of the roller 2. The thickness of projection 7, conjointly with the speed at which the fabric passes through the rollers, causes the roller 2 to bounce up (the lift being in practice greater than the difference between the thickness of projection 7 and that of the fabric F) so that a very substantial displacement of the roller is achieved. This roller displacement may if necessary be multiplied or amplified by suitable apparatus (of which numerous forms are well known) indicated diagrammatically at 40 in Fig. 1; for example simple lever mechanism or gear mechanism or a combination of the two, may be employed for the amplification. The ratio of amplification, if any, may be quite small and in this connection it is to be observed that in Fig. 1 the milling machine 1 is shown on a much smaller scale than the mechanism 9, and that each lift of roller 2 is only required to produce one third of a complete rotation of one shaft 21 mentioned in the following paragraph. As the finger 10 advances it engages a projection 13 on the finger 11 and carries the latter with it but when the finger 10 is returned to the zero position under the influence of a restoring spring 14 the finger 11 remains in its furthest position of advance and so indicates the maximum reading achieved by finger 10.

Each time the roller 2 lifts it operates through means shown diagrammatically in Figure 1 to raise a plunger 15 which, through the medium of a compression spring 16, raises a tube 17 to which a rack 18 is attached, the tube 17 and the rack being thereafter returned by gravity, or a spring such as 19, or by both means to a rest position which may be set by a stop screw 37. The rack 18 engages a pinion 20 loosely mounted on shaft 21 but arranged to drive the latter in a clock-wise direction Fig. 1 through pawl and ratchet mechanism 22. Shaft 21 carries two cams 23, 24. Cam 23 controls the clutch, and cam 24 operates a check pawl 25 pivoted at 26 and urged by spring 27 to a position in which it engages a ratchet wheel 28 (carrying finger 10) and prevents the latter from rotating in a counter-clock-wise direction.

The clutch as shown in Fig. 3 as comprising two members 29 and 30, member 29 being formed on a sprocket 31 which is driven from the worm gearing 8 and member 30 being formed on the ratchet wheel 28. To engage the clutch, member 29 is shifted axially for which purpose there is a fixed cam member 32 and a movable cam member 33 provided with an arm 34 which is drawn by

spring 35 into a position in which it is arranged to be engaged by cam 23.

It will be appreciated that owing to the thickness of the projection 7, and the speed at which that element passes between the rollers, the roller 2 is bounced up with considerable force sufficient to overcome friction and spring pressure in the mechanism (just described) to which that displacement is applied.

In the condition shown in Figures 1 and 2 the clutch 29, 30 has just been engaged following the first pass of the seam 7 through the nip between the two rollers 2, 3 and therefore the ratchet wheel 28 and finger 10 are driven in a clock-wise direction from the reduction gearing 8; the finger 10 drives finger 11 in front of it by means of the projection 13. At the next pass of the seam 7 shaft 21, together with these cams 23, 24, is racked through 120° to the position shown in Fig. 4. In this movement cam 23 makes contact with a lever 34 and rotates the cam member 33 so that the clutch member 29 is permitted to disengage from the clutch member 30. The fingers therefore cease to revolve but finger 10 is prevented from being returned to zero by spring 14 because the check pawl 25 is still engaged with the ratchet wheel 28. At the next pass of the seam 7 shaft 21 is racked through a further 120° to the position shown in Fig. 5. In this position cam 23 still makes contact with lever 34 so that the clutch remains disengaged, but cam 24 makes contact with the end of the check pawl 25 and disengages the latter from the ratchet wheel 28. The spring 14 therefore rotates the ratchet wheel 28 in a counter-clock-wise direction and returns the finger 10 to zero. Finger 11 remains in the position to which it has been driven.

This completes the three phase cycle, and at the next pass of the seam 7 shaft 21 is racked through a further 120° bringing the various parts to the position shown in Fig. 1 in which the check pawl 25 is engaged with the ratchet wheel 28 and the lever 34 is swung in the clock-wise direction so that the cam 33 is given a movement of partial rotation over cam 32 and thereby shifts the clutch member 29 to engage the clutch member 30. The finger 10 is therefore driven forward once again and the cycle is repeated.

It will therefore be appreciated as the milling operation progresses the finger 10 will indicate progressively decreasing lengths, and the fact that the finger 11 remains in a position indicative of the initial length permits an appreciation of the proportionate length reduction to be made with facility.

It will on occasion be necessary to run the milling machine with no fabric in it and it is therefore necessary to ensure that under these circumstances the clutch does not remain engaged so that the fingers 10 and 11 are driven repeatedly around the dial until the spring 14 is broken. For this purpose there may be a safety device comprising a stop member 36, Fig. 1 so placed as to be engaged by one of the fingers after the permitted maximum movement and to be shifted by it so as to cause the lever 34 to be swung to the clutch-disengaging position. Stop member 36 is supported by a lever 41 pivoted at 42 and connected by a link 43 to lever 34. Thus when stop member 34 is moved to the right in Fig. 1, lever 34 is moved to the clutch-disengaging position.

If, instead of the length-representation being a length measurement as in the example described and illustrated, it is a time-measurement that is obtained and exhibited by a "stop-watch"

mechanism it will readily be appreciated that the starting, stopping, and resetting of this mechanism may be controlled by the lift of roller 2 at three successive passes of thickness 7.

The appropriate thickness at 7 may be produced by rolling up or folding up the ends of the fabric band and then sewing such rolled up or folded up ends together.

I claim:

1. In a machine for milling an endless band of fabric having a local projection at one point, at least one driven roller for advancing the fabric, a measuring apparatus driven in synchronism with said driven roller, a clutch in the drive to said measuring apparatus, a displaceable member in the path of said projection to be displaced thereby, and means whereby successive displacements of the member serve to engage and disengage the clutch.

2. In a machine for milling an endless band of fabric having a local projection at one point, a driving roller for feeding the fabric, a resilient displaceable member in the path of said projection, a first indicator movement driven in synchronism with said roller and a second indicator movement actuated by the displacements of said displaceable member, said movements cooperating to indicate an increase in frequency in such displacements.

3. In a milling machine of the type comprising a pair of rollers between which an endless band of fabric is passed repeatedly, a crimp box into which the fabric passes from the rollers and in which it is accumulated and from which it is withdrawn to pass between rollers again, and pressure means for pressing upon the accumulated fabric in the crimp box; apparatus for obtaining and exhibiting at each of successive passes of the fabric band a measurement which is representative of the length of the band at that pass, which apparatus comprises a rotary measuring device that engages the fabric, a length indicator, means driving the indicator in conformity with the measuring device, a resilient mounting for one of said rollers, displaceable in response to the passage through the machine of a local thickness in the fabric, and means operable by such displacement for causing the indicator to be reset for a fresh indication.

4. A machine according to claim 3, having a clutch in the drive to the indicator for connecting and disconnecting the drive, restoring means for returning the indicator to zero upon disconnection of the drive, and means operable by the said displacement to control the clutch.

5. A machine according to claim 3, having a maximum reading indicator movable by the length indicator to indicate the maximum reading achieved by it.

6. A machine according to claim 3, having a maximum reading indicator movable by the length indicator to indicate the maximum reading achieved by the latter, a clutch to the drive of the indicator for connecting and disconnecting the drive; restoring means for returning the indicator but not the maximum reading indicator to zero upon disconnection of the drive, and means operable by the feeler for controlling the clutch.

7. In a machine for milling an endless band of fabric having a local projection at one point, a pair of squeezing rollers one of which is resiliently mounted for displacement by the passage of said projection between the rollers, and an indicator

comprising a first clutch member driven synchronously with said squeezing rollers, a second clutch member and an indicator connected therewith, spring means tending to return said indicator to a zero position, a ratchet and pawl device restraining said indicator against return, clutch engaging and disengaging means, and a cam device operated by displacement of said resiliently mounted roller, successive movements of said cam device operating the clutch engaging and disengaging means and releasing the indicator from said ratchet and pawl device.

8. A machine as claimed in claim 7, wherein said cam device is a uni-directional rotary cam having in series an idle phase of 120° a clutch operating phase of 120° and a ratchet and pawl operating phase of 120° .

9. A machine for milling an endless band of fabric having a local projection at one point, combined with an indicator comprising a step-by-step rotary cam, reciprocating means for rotating said cam, a rotary indicator shaft, driving means for said shaft, an indicator finger, a clutch connecting said indicator to the indicator shaft means operated by said cam for engaging and disengaging the clutch, spring means tending to return the indicator to a zero position, a ratchet and pawl device opposing the return of said indicator, and means operated by the cam to release the indicator from said ratchet and pawl device, and having means for rotating the indicator shaft synchronously with the movement of the fabric, and further means operating the reciprocating means on each passage of said projection.

10. In a milling machine of the type operable upon an endless band of fabric, which endless band is circulated through a crimp box in which a length of the band is always accumulated and subjected to pressure, apparatus for obtaining and exhibiting at each of successive circulations of the fabric band a measurement which is representative of the length of the band at that circulation, which apparatus comprises a rotary measuring device that engages the fabric, a length indicator, means driving the indicator in conformity with the measuring device; a feeler responsive to the passage through the machine of a local thickness in the fabric, and means operable by the feeler response for causing the indicator to be reset for a fresh indication.

11. In a machine for milling an endless band of fabric, a rotary length-measuring device engaging the fabric band, a measuring apparatus, driving connections including a clutch for driving said apparatus in synchronism with the said device, means for detecting the passage of a predetermined point in the endless band, and means whereby successive detectors produce engagement and disengagement of the clutch and the intermittent drive of the measuring apparatus.
